UNITED STATES PATENT OFFICE

2,447,999

PORTABLE PHONOGRAPH

Louis C. Kalff, and August N. Legras, Eindhoven, Netherlands, assignors to Hartford National Bank and Trust Company, Hartford, Conn., as trustee.

Application January 29, 1943, Serial No. 474,001
In the Netherlands March 11, 1941

Section 1, Public Law 690, August 8, 1946
Patent expires March 11, 1961

5 Claims. (Cl. 274—2)

1 This invention relates to a sound reproducing system, and more particularly to portable phonographs wherein the pick-up is united with the driving motor of the turntable, a stopping device and with further appliances in a case or cabinet to form a readily portable unit.

Portable phonographs are known in which the turntable is so united with the lid that when the case is opened the turntable and pick-up are accessible for manipulation. These systems are, however, rather heavy by reason of the many component members.

In addition, it is known to use a turntable of a table model type phonograph as a lid for the case. In this well-known construction the turntable remains, however, seated on the driving and supporting spindle even when acting as a lid so that the turntable cannot close the case in a dust-free manner for constructional reasons. This construction is therefore not well adapted for portable sets.

The invention has for its object to provide a portable phonograph in which the lid of the case also acts as a turntable and in which a satisfactory dust-free closure of the case can be obtained.

According to the invention, the turntable, when being used as a cover, is removed from the supporting shaft.

This may be ensured for example by equipping the said supporting spindle with a detachable top which when the apparatus is being closed is removed between turntable and bearing.

According to the invention, the supporting shaft of the turntable is preferably arranged eccentrically in the case. Thus, when records are being played the lid occupies a place on the case different from that when the case is shut so that it is possible to meet constructional requirements as regards both the lid and the turntable.

One embodiment of the invention particularly serving this purpose comprises a phonograph system housed in a cylindrical case whose cylindrical wall is provided with a handle. In this case, the lid has a cylindrical closing edge and a circular upper surface which is suited to serve as a turntable.

In order that the invention may be clearly understood and readily carried into effect it will now be described more fully with reference to the accompanying drawing, whilst at the same time further features of the invention will be set out.

Fig. 1 is a longitudinal sectional view of the

2 portable phonograph according to the invention with closed lid.

Fig. 2 is a plan thereof showing the lid while being used as a turntable.

5 Referring to the figures, 12 designates the cylindrical box which serves as a case or cabinet for the phonograph system. On the upper side, that is to say on the side where the turntable and the pick-up 14 are arranged, this box is closed 10 by a circular lid 10 provided with cylindrical edges 9 closing around the box 12. On its inside surface the lid is provided at the centre with a hub 11 comprising a conical aperture. This aperture 8 fits around the conical end of a spindle 19. 15 This spindle, which is arranged eccentrically in the box 12 near the wall, only serves to support the turntable 10. The driving force is supplied from a small electric motor 20 arranged below the mounting plate 15. The drive is effected by 20 means of a small friction roller 18 on the cylindrical edge of the turntable 10.

In order that in the use as a turntable the cylindrical sides of the lid 10 may be passed through the apparatus a cylindrical slot 16 is formed in the mounting plate 15. This slot extends on both sides into the outer wall 12 so that the turntable 10 can turn outside the apparatus in an unhampered manner.

In addition, the space below the mounting plate 30 15 may be used for housing the switching-off mechanism and also any accessories such as the amplifier 17 associated with the apparatus. The space below it is arranged as space for storing flexible leads and also some records. These records 35 21 are resiliently pressed against a lowered part of the bottom plate 23 of the apparatus by means of three small resilient, e. g. spring-pressed rods 13 having bent-over ends.

In order to facilitate the carrying of the apparatus in the closed condition the box 12 is provided on the cylindrical circumference with a leather handle 22.

The term "phonograph" as used throughout this specification and the appended claims is intended to cover sound recording as well as sound reproducing systems.

Having now described our invention, what we claim is:

50 1. A phonograph, comprising in combination, a case, a combination cover and turntable member removably associated with said case, a flange on said member whereby to fit it concentrically over said case during service as cover, a centric hub on said member for mounting it rotatably in said case during service as turntable, a top plate

in said case, a spindle eccentrically mounted in said top plate for supporting said hub, a channel in said top plate and extending through said case wherein to accommodate said flange in its eccentric position, and a drive member extending into said channel to act on said flange.

2. A phonograph, comprising in combination, a vertically cylindrical case, a circular combination cover and turntable member removably associated with said cylindrical case, a circumferential flange on said member whereby to fit it concentrically over said cylindrical case during service as a cover, a centric hub on said member for mounting it rotatably in said case during service as turntable, a top plate in said case, a spindle eccentrically mounted in said top plate for supporting said hub, a channel in said top plate and extending in an arc through said case wherein to accommodate said flange in its eccentric position, and a drive member extending into said channel to act on said flange.

3. A phonograph, comprising in combination, a vertically cylindrical case, a circular combination cover and turntable member removably associated with said cylindrical case, a circumferential flange on said member whereby to fit it concentrically over said cylindrical case during service as a cover, a centric hub on said member for mounting it rotatably in said case during service as turntable, a top plate in said case, a spindle eccentrically mounted in said top plate for supporting said hub, a channel in said top plate and extending in an arc through said case wherein to accommodate said flange in its eccentric position, a drive member extending into said channel to act on said flange, and a pick-up arm pivotally mounted on said top plate outside the arc of said channel whereby said pick-up arm may be positioned beneath said combination cover and turntable member when said member is in service as a cover and above said combination cover and turntable when said member is in service as a turntable.

4. A phonograph, comprising in combination, a case, a combination cover and turntable member removably associated with said case, a flange on said member whereby to fit it concentrically over said case during service as a cover, a centric hub on said member for mounting it rotatably in said case during service as turntable, a top plate in said case, a spindle eccentrically mounted in said top plate for supporting said hub, a channel in said top plate and extending through said case wherein to accommodate said flange in its eccentric position, a drive member extending into said channel, and a friction roller on said drive member for engagement with said flange.

10

5. A phonograph, comprising in combination, a case, a combination cover and turntable member removably associated with said case, a flange on said member whereby to fit it concentrically over said case during service as a cover, a centric hub on said member for mounting it rotatably in said case during service as turntable, a top plate in said case, a spindle eccentrically mounted in said top plate for supporting said hub, a channel in said top plate and extending through said case wherein to accommodate said flange in its eccentric position, a drive member extending into said channel to act on said flange, and motor means housed in said case beneath said top plate and operatively associated with said drive member.
